UNITED STATES PATENT OFFICE.

HAROLD E. BETTON, OF LYNN, MASSACHUSETTS.

COAL CHUTE.

Application filed April 17, 1924. Serial No. 707,306.

To all whom it may concern:

Be it known that I, HAROLD E. BETTON, a citizen of the United States, residing at Lynn, in the county of Essex and State of Massachusetts, have invented certain new and useful Improvements in Coal Chutes, of which the following is a specification.

The invention to be hereinafter described relates to apparatus for piling coal and other material.

It is customary to store coal in pockets, bins, and on the ground in large piles, and sometimes these piles are 35 or 40 feet high. In building up these piles, the coal is conducted to an elevated level and if allowed to drop therefrom to the ground or floor on which the piles are to be placed, the distance is so great, and especially in starting the piles, that the coal becomes broken to a large extent, thereby reducing its market value.

In attempting to prevent breaking of the coal, it has been conducted from the elevated level toward the floor by chutes of different kinds, and some of these have been designed with the object of delivering the coal with a short drop to prevent the breakage of the coal referred to. However, so far as I am aware, none of these chutes has been satisfactory for the purpose.

The aim and purpose of the present invention, therefore, is to provide a chute which will build up the pile by delivering the coal at progressive intervals along the length of the chute, the construction being such that the coal will have a substantially uniform short fall. In carrying the invention into practical effect, in the present instance, the chute is provided with a series of gates or hinged sections which are automatically, progressively opened by rise or backing up of the coal in the chute. The gates are opened by the direct engagement of the coal therewith, thereby eliminating the necessity of complex releasing devices which are unreliable in their operation.

The character of the invention may be best understood by reference to the following description of one good form thereof shown in the accompanying drawings, wherein:

Figure 1 is a vertical longitudinal section through a chute embodying the invention taken on line 1—1 of Fig. 2, and showing a coal pile in process of being built up and

Fig. 2 is a plan of the chute.

Referring to the drawings, the chute

shown therein as one good form of the invention, comprises a suitable support, in the present instance, in the form of a pair of side plates 1 of steel or other suitable material, said plates being spaced and connected at intervals by bridge bars 3. These plates are of sufficient length to extend from the coal receiving level 5 down to the floor 7. The lower end of the chute may rest upon the floor, and the upper end thereof may be provided with any suitable support not shown.

The chute, in the present instance of the invention, has a series of troughs or sections including fixed sections 9 and movable sections 11 desirably in alternating relation. These troughs or sections may be formed of steel or other suitable material.

The fixed troughs comprise floors 13 which may extend between the plates 1, and have flanges 15 riveted or otherwise secured to said plates. Rising from the floors 13 are sides 17, in the present instance, converging downward and spaced a substantial distance from the plates. The convergence of the sides tends to retard the flow of the coal.

The movable troughs or gates comprise floors 19 and sides 21, in the present instance, substantially parallel to the plates and having their lower ends set in somewhat from the vertical planes of the sides 17 of the fixed troughs, thereby effectively to deliver the coal from the movable to the fixed sections. The sides 21 of the movable sections are spaced a sufficient distance from the plates 1, so that any coal coming between the sides and the plates cannot jam between them and interfere with free movements of the movable troughs.

The movable troughs may be tiltably mounted, and in the present instance, have hinges in the form of straps 23 secured to the floors 19, and receiving through rods 29 which are secured to the plates 1. These hinges are located intermediate the ends of the movable sections, and are offset downward somewhat away from the centers of gravity of the sections, so that the tendency of the sections will be to gravitate to closed positions.

Suitable means may be provided to limit the tilting movements of the sections. To accomplish this, in the present instance, stop pins 31 are mounted on the plates 1, and extend inward a sufficient distance to be engaged by floors of the movable sections. The

opening movements of the tilttable sections may be limited by engagement of the upper edges of the sides of the sections with the bridge bars 3 referred to, said bridge bars 5 being appropriately located at intervals along the length of the side plates for this purpose.

At the upper end of the chute is a fixed section 33 longer than the fixed sections 10 above described, and having sides 35 which diverge outward to the upper ends of the plates 1. In the floor of the upper fixed section 33, is an opening 37 provided with a pair of doors 39 connected to the floor of 15 the upper section by hinges 41, said doors being secured in closed position by a lock rod 43 entered through eyes in straps 45 secured to the floor of the upper fixed section.

20 In the use of the chute, it is placed in the desired location, and preferably at an angle of about 30°. The coal introduced to the upper end of the chute will slide down along the floors of the fixed and movable sections, 25 and will discharge and form a pile at the lower end of the chute. The coal will accumulate and will rise or back up into the chute until a sufficient amount is on the lower end portion of the lowest movable trough, 30 to tilt the same to open position. Thereupon, the coal will be discharged from the fixed trough which is directly above the lowest movable trough. The coal will continue to flow therefrom, and will build up the pile 35 beneath the chute. When the coal reaches the under surface of the floor of the lowest tilttable trough, it will rock the same almost back to its closed position.

40 The coal will then back up in the chute until the coal reaches the lower portion of the second tilttable trough. This will tilt the trough, as shown in Fig. 1, and then the coal will be discharged from the fixed trough which is directly above the trough last tilted.

45 The coal will continue to back up in the troughs as the height of the pile increases, and the movable troughs will be progressively opened and closed as described until the top of the pile approaches the upper fixed section 33. Thereupon, the doors 39 may be opened, and the coal may flow through the opening 37, thereby to complete discharge of coal to the pile.

55 The construction is such that the coal is discharged from the chute at progressive points up along the length thereof, and the drop of the coal from the chute to the pile is always a distance sufficiently short to prevent material breakage of the coal. The flow of the coal in the chute is retarded by the converging sides of the fixed troughs.

60 Under some conditions the side plates 1 may be made somewhat higher than those shown, and a roof may be mounted on said sides to close in the chute.

After the pile has been completed and coal is withdrawn therefrom, as by loading it into trucks, the coal will fall away from the under surfaces of the troughs which were nearly closed by rise of coal beneath them, 70 and allow the troughs to completely close under the influence of gravity, so that their floors will be flush with the floors of the fixed troughs and in readiness again to conduct coal to build up the pile. 75

It will be noted that when the tilttable troughs are in closed positions, their centers of gravity are at the right of their hinges and consequently they tend to remain in closed positions automatically. When sufficient coal backs up and accumulates on the lower ends of the tilttable troughs they will rock to open positions in which they are limited by engagement with the bridge bars 3 as shown in Fig. 1. In the course of this 85 movement the centers of gravity of the troughs will shift from the right to the left of their hinges and consequently they tend to remain in open positions automatically. They remain open until the coal pile rises 90 to the under sides of the troughs and rocks the same toward closed positions as described.

If large lumps of coal should become clogged between the converged sides of a 95 fixed trough above any tilttable trough, the coal will back up in the clogged trough and accumulate on the lower end of the tilttable trough next above the clogged trough, thereby causing the tilttable trough to open and 100 start a coal pile in advance of the lower end of the chute. When the pile rises to and closes the trough thus opened, the coal will flow down to the clogged trough and the impact may be sufficient to clear the clogged trough. If so a coal pile will thereafter be built up nearer the lower end of the chute. It is not probable that any of the fixed troughs will be so clogged with coal as to 105 require manual clearing. 110

The chute is broken away for convenience of illustration, it being understood that the length of the chute may be varied according to conditions as required.

In order that the coal may be directed 115 toward the center of the bin or pocket, a chute is located along each wall of the pocket so that the coal piles inwardly from the wall as each chute is used building up in the central space. 120

Where the depth of the pocket is too great to permit efficient delivery with a chute set at the angle illustrated, then the usual expedient of providing two chutes, the lower end of one delivering to the upper end of 125 the other, may be employed. It may happen that a single chute can be accommodated to a deeper pocket by setting it at a greater angle of inclination than is illustrated, and this may be done with satisfactory results 130

within a certain range of angles. Whenever the angle of inclination of the chute is increased, then the rod 29 on which the tilt-
able sections 19 pivot must be moved for-
wardly to shift the center of gravity and
provide for the sections closing automatical-
ly as hereinbefore described. Accordingly,
each side wall 1 of the chute is provided with
a series of slots 47 within opposite pairs of
which a rod 29 may be moved longitudinally
of the chute, the traps 23 first being discon-
nected from the sections and then bolted up
again after the proper new position of the
rod has been determined. The rods 29 are
held in any required position in the slots
47 by nuts 49 on the ends thereof. The sec-
tions 19 are held in their central positions
on the rods by collars 50 suitably secured to
the rods.

20 The nature and scope of the invention
having been indicated and its preferred em-
bodiment having been specifically described,
what is claimed as new, is:—

1. Apparatus for piling material, com-
prising an inclined chute having fixed and
tiltable floor sections in alternating rela-
tion, said tiltable sections being adapted for
conducting material from fixed section to
fixed section, and said tiltable sections be-
ing free to be tilted automatically to dis-
charge positions by rising of the piled ma-
terial in the chute onto the lower portions
of the tiltable sections.

2. Apparatus for piling material, com-
prising an inclined chute having a floor
composed in part of tiltable floor sections
adapted for conducting material, said til-
table sections having hinges so located that
the sections tend to gravitate to closed posi-
tions each with its upper end on top of the
lower end of the section next above it, and
said upper ends being free to be tilted up-
ward automatically by rise of the piled ma-
terial in the chute progressively onto the
lower portions of the tiltable sections.

3. Apparatus for piling material, com-
prising an inclined chute having tiltable
floor sections for conducting material, said
sections being tiltable on fulcra intermediate
their ends so located that the sections tend
to gravitate to closed positions, and each
section being free to be tilted automatically
to a discharge position by material rising
in the chute onto the upper side of the por-
tion below its fulcrum and to be tilted to-
ward closed position by material rising be-
neath the chute into contact with the under
side of said portion.

4. Apparatus for piling material, com-
prising an inclined chute having side walls,
a series of sections in said chute each hav-
ing side walls spaced substantial distances
from the walls of the chute to permit excess
material readily to fall therebetween, alter-
nate sections being tiltably mounted on

fulcra between their ends, and each said
tiltable section gravitating into the general
plane of the remaining sections with the
lower ends of its side walls resting inside
the side walls of the next adjacent section 70

5. Apparatus for piling material, com-
prising an inclined chute having a floor com-
posed of alternate fixed and pivotally
mounted floor sections including a transverse 75
pivot for each of said latter sections posi-
tioned intermediate the ends thereof and
arranged to cause the upper end of a pivoted
section normally to engage the upper side of
the fixed section next above it and its lower
end to engage the under side of the fixed 80
section next below it, whereby a pivoted
section may tilt in a manner to permit dis-
charge of material beneath it through the
floor opening in the chute floor thus formed 85
above it.

6. Apparatus for piling material, com-
prising an inclined chute formed of a series
of alternate fixed and tiltable floor sections,
said tiltable sections being hinged on fulcra 90
mounted on the chute but adjustable beneath
said tiltable sections to shift the center of
gravity thereof longitudinally.

7. Apparatus for piling material, com-
prising an inclined chute having tiltable sec-
tions the longitudinal position of which in
the chute is unalterable, and pivot rods for
said sections adjustably mounted to vary
their position lengthwise of the tiltable 95
sections.

8. Apparatus for piling materials, com-
prising an inclined chute having side mem-
bers, a series of tiltable sections mounted
on pivot rods, the ends of which extend into
longitudinal slots formed in said side mem-
bers, and means for securing said rods in
different positions along said slots relative
to said sections.

9. Apparatus for piling material, com-
prising an inclined chute formed of a series 110
of troughs arranged end to end, alternate
troughs being pivotally mounted and freely
tiltable into open position to act successively
as discharge gates upon the gradual rise
of material in the chute onto the lower por-
tions thereof.

10. Apparatus for piling material, com-
prising an inclined chute having a plurality
of floor sections for conducting material,
each section being tiltable on a transverse 120
fulcrum, so located that its portion above
the fulcrum is heavier causing the section
normally to gravitate to a closed position,
and mounted to be free to tilt to open posi-
tion when its balance is disturbed by over-
weighting the lower portion of the section
as by the rise of material in the chute onto
said portion.
